UNITED STATES PATENT OFFICE.

LEVI SHOOK, OF PITTSBURG, PENNSYLVANIA.

PRESSURE-GOVERNOR AND REGULATING-VALVE.

SPECIFICATION forming part of Letters Patent No. 320,302, dated June 16, 1885.

Application filed March 27, 1885. (No model.)

To all whom it may concern:

Be it known that I, LEVI SHOOK, of Pittsburgh, in the county of Allegheny and State of Pennsylvania, have invented certain new and useful Improvements in Pressure-Governors and Regulating-Valves; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to fluid-pressure-regulating valves, and to that class in which a diaphragm is used, and in which the valves are balanced with reference to the pressure in any position.

The object of my invention is to produce a pressure-regulating valve that will be sensitive to the least variation in the pressure of the fluid, in which the valves will not stick when closed, and in which the valve-stem guides are protected from the governed fluid passing through the regulator.

The figure of drawing shows a vertical section of my invention.

A is the shell, provided with the inlet B and outlet C. The inlet and outlet have the partition D between them, which is provided with two circular openings, that are controlled by the double or puppet valve F F'. The seats E E for this valve are plain surfaces upon the partition. The valve is formed of two disks, and may be in one piece or two, as I have shown them. The seat of the valve a, or the part that comes in contact with the seat E, is sharp, or formed into what is called a "knife-edge" seat. These seats being of equal diameter and occupying no space upon the seats E E, it will be seen that the valve will be balanced to the pressure on the inlet or outlet side of the same.

A stem, S, provided with a collar, e, passes through the valve, and the latter is held upon the same by the nut f.

Upon the lower part of the shell is a cap, K, having a cup or recess, H, formed in it and in line with the valve-stem. About midway of the cup guides h h are formed for the lower end of the valve-stem.

Through the bottom of the cup is inserted a screw, I, which is directly below the valve-stem. By operating the screw the valve may be adjusted to regulate the amount of fluid allowed to pass or closed entirely. This screw 55 is provided with a jam-nut, i, for holding it in position when set.

The cup is filled with mercury or glycerine, to protect this guide h from the action of the fluid passing through the valve, thereby preventing the stem from sticking by corrosion or any gummy substance.

To the upper part of the shell is attached the diaphragm-chamber L, which is composed of an upper and a lower part, and between which 65 is held a flexible diaphragm, M.

Where the stem passes through the diaphragm, washers N O are provided, one on each side of the diaphragm, the washer on the lower side being smaller than that on the upper, the 70 object being to allow for a free movement upward and a limited movement downward, but sufficient to give a free opening to the valve.

The diaphragm is fastened to the stem by a nut, b, that clamps the washers against the 75 shoulder d on the stem.

To the top of the chamber L is secured a spring-chamber, Q, and into the end of this chamber is screwed a hollow bolt, R, that serves to guide the upper part of the valve-stem, and 80 also to adjust the tension of the spring P, which is placed between the bolt and the diaphragm, the tendency of the spring being to keep the valves open.

The operation is as follows: Steam, water, or 85 gas passing in at B flows by the valve until a pressure is reached to which the spring is set, when the back-pressure, acting upon the diaphragm, overcomes the tension of the spring, and closes or partly closes the valve, thus 90 regulating the supply to the demand at the predetermined pressure.

Having described my invention, what I claim is—

1. In a fluid-pressure regulator, the combination of the stem, the two disk-valves formed with knife-edges, the diaphragm, the washers on each side thereof, and the spring bearing on the upper of said washers with a tendency to 95 keep the valve normally open, and the tubular 100

nut to receive the stem and regulate the force of said spring, as set forth.

2. In a fluid-pressure regulator, the combination of a cup, provided with guides for the 5 valve-stem, with the valve-stem and the contained metal or fluid in the cup for protecting the stem, substantially as described.

3. In a fluid-pressure regulator, the combination of a cup, provided with guides for the 10 valve-stem, with the valve-stem, the adjusting or closing screw, and the contained fluid in the cup for protecting the stem, substantially as described.

4. In a fluid-pressure regulator, the combination of the double knife-edge valve, the 15 valve-stem, the lower fluid-protected guide for the stem, with the diaphragm and the spring-adjusting and valve-stem guide-bolt, substantially as and for the purpose set forth.

In testimony that I claim the foregoing as my 20 own I affix my signature in presence of two witnesses.

LEVI SHOOK.
